TYPOGRAPHICAL SLUG CASTING
MACHINE

Christian Augustus Albrecht, Berlin, Germany,
assignor to Mergenthaler Linotype Company,
Brooklyn, N. Y.

Application November 28, 1934, Serial No. 755,127
In Germany December 22, 1933

12 Claims. (Cl. 199—50)

This invention relates to typographical slug casting machines, such as those known commercially under the registered trade mark "Linotype", wherein a composed line of matrices is clamped between two vice jaws for presentation to the casting mechanism. More particularly the invention relates to mechanism for automatically centering a matrix line relatively to the casting mold slot or quadding a short matrix line to one side or the other of the cast slug, and is an improvement in or modification of the mechanism described in the specification of my application for Letters Patent Serial No. 711,119, filed 14th February 1934.

Such centering and quadding mechanism comprises a vertically movable rod which operates through a disc or collar, upon studs carried by levers connected to the adjustable jaws, the said disc or collar being provided with gaps which can be positioned, by rotation of the collar, to actuate either or both of the jaws. When both jaws are operated the line will be centred, when either jaw is operated independently the line will be quadded to one side or the other, and when both jaws are disconnected, the device will be inoperative. The said mechanism further includes means for tightening the line clamping jaws on to the line after justification, the said means comprising a pawl and ratchet wheel with teeth on a portion only of its periphery adapted to effect the desired jaw-tightening movement of the jaw-actuating rod, through a pinion acting on a rack connected to the rod.

When full lines are cast this device is thrown out of action in order to obtain justification to expand the line to full length, and for adaptation to different full line lengths (which are determined by the set position of the adjustable jaw, usually the left-hand jaw) the pawl for engaging the ratchet wheel is adjustable to different positions along the untoothed portion of the ratchet wheel to vary the extent of rotation of the ratchet wheel during justification before its teeth come into position to be engaged by the pawl. If, for example, the pawl is adjusted to allow for a 2 em expansion during justification and the line is composed within 2 ems or less of the full line length the ratchet wheel will not be rotated sufficiently by the operation of the device in closing the jaws on the line to bring its toothed portion into position to be engaged by the pawl, so that the pawl, resting on the untoothed portion of the ratchet wheel, when actuated will not rotate the ratchet wheel to clamp the jaws on the line and the jaws will remain free to move back to full line

position under the expanding influence of the spacebands; whereas, if the composed line is more than 2 ems short of the full line length the ratchet wheel will be rotated sufficiently during the jaw closing operation of the device to bring its toothed portion into position to be engaged by the pawl and during justification the actuation of the pawl will effect the rotation of the ratchet wheel to clamp the jaws against the line in quadding condition and prevent abnormal justification. For the purpose of adjusting the pawl relatively to the ratchet wheel, according to the specification of my above mentioned patent application, the pawl is pivotally mounted on a lever capable of being rocked about the axis of the ratchet wheel, so that the pawl is adapted, respectively, for engagement and disengagement with the teeth on the ratchet wheel and for being adjusted relatively to the ratchet wheel to a number of different positions, by a manually operated lever.

According to the present invention, the adjustment for lines of different length is effected by adjusting the ratchet wheel instead of the pawl. In carrying out the invention, a sleeve mounted upon the jaw-actuating rod is provided with circumferential ribs of rack-like form in profile with which the before-mentioned pinion engages, and the sleeve is threaded upon a relatively stationary screw, so that when the sleeve is rotated by an adjusting lever, it will be moved axially and thereby the pinion which is located upon the same axis as the ratchet wheel, will be turned an amount corresponding to the axial movement of the sleeve, thereby rotating the ratchet wheel relatively to the pawl to increase or diminish the distance between the pawl and the toothed portion of the ratchet wheel.

The accompanying drawing illustrates one constructional form of the invention, and in the said drawing:

Figure 1 is a front elevation partly in section of the pertinent parts of the machine;

Figure 2 is a vertical section of a portion of Figure 1;

Figure 3 is a horizontal section taken on the line 3—3 of Figure 1;

Figure 4 is a horizontal section on the line 4—4 of Figure 1, and

Figure 5 is a horizontal section on the line 5—5 of Figure 2, on an enlarged scale.

As in the before-mentioned prior arrangement, 2, 3 are the line-clamping jaws, which may be centred or moved towards one another. The operation of the levers 6 and 7 is controlled by a

rod 33 under the action of springs 48. According to the invention, a sleeve 124 mounted upon the rod 33 is provided externally with a circumferentially ribbed portion, which in section is in the 5 form of a rack, so that the pinion 62 may engage therewith and, in the manner described in the before-mentioned specification, by means of the pawl and ratchet wheel 64, 65, engaged and rotated by a collar 77^a on the justification lever 10 77, so actuate the rod 33 that the tight clamping of the line will be effected. The object in view is to so adjust the ratchet wheel 64 relatively to the pawl 65, that, according to the adjustment made, the path travelled by the ratchet 15 wheel before the toothed portion is engageable by the pawl, will be varied, the adjustment being so calculated that it will approximately correspond to the justification capacity of the spacebands normally present in a line of given length, for 20 example, one em for short lines, two ems for medium length lines and three ems for long lines. For this purpose, a control lever 125 is provided which can be adjusted to a number of different positions according to a scale 126. The 25 lever, pivoted about the fulcrum 127, is connected at its lower end by means of a link 128 to a sliding rack 129 which meshes with teeth 130 on the lower end of the sleeve 124. The rod 33 passes through the sleeve 124. The lower end of 30 the sleeve is internally threaded and the threaded portion engages an enlarged threaded portion 131 of an inner sleeve 131^a surrounding the rod 33. In order to couple the sleeve 131^a with the rod 33, so as to ensure that it will be secure 35 against rotation, a disc 132 (Figures 2 and 5) is secured to the rod by a pin 132^a and provided with slots in which are engaged downwardly directed fingers 133 of the sleeve 131^a, and upwardly directed fingers 134 formed on a sleeve 33^a 40 through which the lower part of the rod 33 passes and is anchored by a member 33^b fitted in the end of the sleeve and screwed on the end of the rod. The sleeve 33^a is held against rotation by a feather connection 135 with a fixed bearing 136 through which it passes; while the rod 33, in turn, has a feather connection 137 with the sleeve 33^a, and because of the feather on the rod 33 the disk 132 is formed with a 45 notch 138 to permit it to pass over the feather during assemblage of the parts. The movement 50 of the pawl 65 is effected by the justification bar 77.

It is pointed out that the rod 33, sleeves 33^a, 124 and 131^a constitute a composite rod which moves as a unit when pulled downwardly by the 55 springs 48 to close the jaws together, when acted upon by the pinion 62 to lock the jaws in their inwardly moved position and when raised again (by the first elevator) to return the jaws to their 60 full line position. A pair of springs 105 and 106, heavier than the springs 48, allow the sleeves 124 and 131^a to move as a unit a slight extent relatively to the rod 33 in the event that the pawl 65 engages very closely and without any play on the 65 teeth of the ratchet wheel 64 and the wheel is unable to turn, all as set forth in the application, Serial Number 711,119 referred to heretofore. This relative movement of the sleeves is permitted by the sliding engagement of the fingers 70 133 on the sleeve 131^a with the disk 132.

The mode of operation is as follows:—

Adjustment of the hand lever 125 will, through the link connection described, actuate the sliding rack 129 and thereby turn the sleeve 124. As 75 the ribs located thereon constitute a rack, this

turning and the consequent axial movement of the sleeve with its ribs in engagement with the pinion 62, will cause the latter and therewith the shaft 35 of the said pinion to turn. Consequently, a corresponding rotation of the ratchet wheel 64 will also take place and its adjustment effected in the desired manner. If the unexpanded length of the composed line presented between the jaws is short of full line length by the amount indicated on the scale 126 according to 10 the adjustment of the hand lever 125, or a lesser amount, the jaws can only be moved inwardly by the downward movement of the rod 33 to an extent equal to the difference between full line length and the unexpanded length of the composed line. The ratchet wheel 64, therefore, will not be rotated by the downward movement of the rod 33 sufficiently to bring its ratchet teeth into position to be engaged by the pawl 65. Hence, during justification, the space bands will expand 15 the line to full length, returning the jaws to their full line position. If, however, the line presented between the clamping jaws is not composed to the proper length and the extent of inward movement of the jaws is greater than the amount indicated on the scale 126 according to the adjustment of the hand lever 125, the ratchet wheel 64 is rotated clockwise (Fig. 1) by the downward movement of the rod 33 sufficiently to bring its 20 teeth into position to be engaged by the pawl 65 and, during justification, the pawl 65 will act through the ratchet wheel 64, pinion 62 and the rod 33 to lock the jaws in their inwardly moved 25 position and prevent expansion of the spacebands. 35

Having described my invention, I declare that what I claim and desire to secure by Letters Patent is:—

1. In a typographical slug casting machine, the combination with a pair of jaws between which a composed line of matrices and spacebands is clamped and a jaw-actuating rod adjustable to close the jaws on to a composed line, of a toothed sleeve on the jaw-actuating rod, a pinion meshing with said toothed sleeve operable to effect a supplemental adjustment of the rod to tighten the jaws against a line after said jaws have been closed thereon, and means operable to adjust the sleeve axially on the rod to vary the angular position of the pinion relatively to a given jaw-closing adjustment of the rod. 40

2. In a typographical slug casting machine, the combination with a pair of jaws between which a composed line of matrices and spacebands is clamped, a justification lever by which the spacebands are expanded to justify the line, and a jaw-actuating rod adjustable to close the jaws on to a composed line, of a toothed sleeve on the jaw-actuating rod, a pinion meshing with said toothed sleeve, a ratchet wheel operatively fast 55 to the pinion, a pawl co-operating with said ratchet wheel and actuated by the justification lever to turn said ratchet wheel to effect a supplemental adjustment of the rod to tighten the jaws against a line after said jaws have been closed thereon, and means operable to adjust the sleeve axially on the rod to vary the angular position of the pinion relatively to a given jaw-closing adjustment of the rod. 60

3. In a typographical slug casting machine, the combination with a pair of jaws between which a composed line of matrices and spacebands is clamped, a justification lever by which the spacebands are expanded to justify the line and a jaw-actuating rod adjustable to close the jaws on to a 70 75

composed line, of a circumferentially ribbed sleeve on the jaw-actuating rod, a pinion meshing with said ribbed sleeve, a ratchet wheel operatively fast to the pinion, a pawl co-operating with said ratchet wheel and actuated by the justification lever to turn said ratchet wheel to effect a supplemental adjustment of the rod to tighten the jaws against a line after said jaws have been closed thereon, a relatively stationary screw on which said sleeve is threaded, and means adapted to turn said sleeve to effect axial movement thereof relatively to the screw and jaw-actuating rod.

4. In a typographical slug casting machine, the combination with a pair of jaws between which a composed line of matrices and spacebands is clamped, a justification lever by which the spacebands are expanded to justify the line, and a jaw-actuating rod adjustable to close the jaws on to a composed line, a sleeve on the jaw-actuating rod having internal threads, a threaded portion of said rod with which the internal threads of the sleeve engage, external circumferential ribs on a portion of said sleeve, external longitudinal ribs on another portion of said sleeve, a pinion meshing with said circumferential ribs, a ratchet wheel operatively fast to the pinion, a pawl co-operating with said ratchet wheel and actuated by the justification lever to turn said ratchet wheel to effect a supplemental adjustment of the rod to tighten the jaws against a line after said jaws have been closed thereon, a sliding rack meshing with the longitudinal ribs on the sleeve, and means adapted to prevent angular movement of the rod.

5. In a slug casting machine, the combination of a pair of line clamping jaws, means for moving one of the jaws toward a composed line of matrices and expansible spacebands, said means including a unitary structure comprising members capable of relative movement, justifying means for expanding the spacebands, supplemental jaw moving means to tighten said jaw against the line, said supplemental means acting through the jaw moving means, and means for effecting a relative movement of said members to adjust the operation of said supplemental jaw moving means.

6. In a slug casting machine, the combination of a pair of line clamping jaws, one movable toward the other for quadding, means for effecting such quadding movement of the jaw to move it toward a composed line of matrices and expansible spacebands, said means including a unitary structure comprising members capable of relative movement, justifying means for expanding the spacebands, supplemental jaw moving means to tighten said jaw against the line, said supplemental means acting through the jaw moving means, and means for effecting a relative movement of said members to adjust the operation of said supplemental jaw moving means.

7. In a slug casting machine, the combination of a pair of line clamping jaws movable equidistantly toward each other for centering, means for effecting such centering movement of the jaws to close upon a composed line of matrices and expansible spacebands, said means including a unitary structure comprising members capable of relative movement, justifying means for expanding the spacebands, supplemental jaw moving means to tighten the jaws against the line, said supplemental means acting through the jaw moving means, and means for effecting a relative movement of said members to adjust the operation of said supplemental jaw moving means.

8. In a slug casting machine, the combination of a pair of line clamping jaws between which a composed line of matrices and expansible spacebands is clamped, means for moving the line clamping jaws toward the line, said means including a unitary structure comprising members capable of relative movement, means for selectively coupling the line clamping jaws to the jaw moving means for quadding or centering a composed line, justifying means for expanding the spacebands, supplemental jaw moving means to tighten the jaws against the line, said supplemental means operating through the jaw moving means, and means for effecting a relative movement of said members to adjust the operation of said supplemental jaw moving means.

9. A combination as in claim 5, wherein the unitary structure comprises a rod and sleeve threadedly connected for relative axial movement.

10. A combination as in claim 5, wherein the unitary structure comprises a rod and sleeve threadedly connected for relative axial movement, and wherein the rod is held against rotation and the sleeve is equipped with teeth for rotation by a sliding rack bar.

11. A combination as in claim 5, wherein the unitary structure comprises a rod and sleeve threadedly connected for relative axial movement, and wherein the rod is held against rotation and the sleeve is equipped with teeth for rotation by a sliding rack bar, characterized by the fact that the extent of relative movement of the rod and sleeve is varied for lines of different lengths and the supplemental jaw moving means is rendered inoperative unless the jaw closing movement of the rod and sleeve exceeds the extent of relative movement of the rod and sleeve.

12. A combination as in claim 5, wherein the unitary structure comprises a rod and sleeve threadedly connected for relative axial movement, and wherein the jaw moving means acts upon the rod and the supplemental jaw moving means acts upon the sleeve, the rod and sleeve being actuated as a unit in each instance.

CHRISTIAN AUGUSTUS ALBRECHT.
